UNITED STATES PATENT OFFICE.

JOHN COULSON, OF WILKINSBURG, PENNSYLVANIA, ASSIGNOR TO WESTINGHOUSE ELECTRIC AND MANUFACTURING COMPANY, A CORPORATION OF PENNSYLVANIA.

ELECTROLYTIC LIGHT SOURCE.

1,419,360.

Specification of Letters Patent. Patented June 13, 1922.

Application filed November 3, 1917. Serial No. 200,042.

To all whom it may concern:

Be it known that I, JOHN COULSON, a subject of the King of Great Britain, and a resident of Wilkinsburg, in the county of 5 Allegheny and State of Pennsylvania, have invented a new and useful Improvement in Electrolytic Light Source, of which the following is a specification.

My invention relates to the production 10 of light, and it has for an object to produce light directly from electro-chemical energy.

Another object of my invention is to produce light without the production of a large amount of heat.

15 Another object of my invention is to produce a source of light that may be safely operated in the presence of explosive gases and atmospheres.

Another object of my invention is to produce 20 a source of light that may be simply and easily constructed.

Another object of my invention is to produce 25 a source of light that may be operated upon electric circuits in which there are large fluctuations of voltage.

A further object of my invention is to produce 30 a source of light that may yield light having particularly desirable qualities and characteristics.

35 A still further object of my invention is to produce a source of light that may be reliable and economical in operation.

I have discovered that, under certain conditions, plates of various metals may be 40 made to emit light when subjected, in a bath, to the action of an electric current.

In the drawing, Fig. 1 is a vertical sectional view of a source of light constructed in accordance with my invention for direct-current energization; Fig. 2 is a corresponding view of a source of light designed for alternating-current energization; Fig. 3 is an elevational view of a tubular lamp constructed according to my invention; Fig. 4 is a sectional view, on an enlarged scale, taken on lines IV—IV of Fig. 3; and Fig. 5 is a sectional view of a modification of the tubular form of lamp.

In Fig. 1, a source of light 1 consists of 50 two electrodes 2 and 3, suspended in an aqueous bath 4 in a transparent container 5. Electrode 2, which may be of aluminum alloyed with manganese or manganese and copper, is connected, as an anode, through 55 a variable resistance element 19, to the posi-

tive terminal of a direct-current battery 6, the negative terminal of which is connected to electrode 3, which may be of carbon or aluminum or other metal or substance which is not soluble in the aqueous bath 4. The 60 bath 4 may contain various compounds commonly used as electrolytes, such as citric acid or the citrate, carbonate, borate or bикарбонат of ammonia.

In operation, electric current is passed 65 from one electrode to the other through the electrolyte, and a film 7 of aluminum hydroxid, the thickness of which is exaggerated in the drawing, is formed upon the surface of the positive electrode 2. It is 70 advisable to regulate the temperature of the bath and the strength of the electric current during the film-forming operation in order to secure a uniform deposit of hydroxid over the entire surface of the filming electrode. After the film has been formed, the 75 source of light 1 is subjected to an electro-motive force which may vary from below 100 volts to above 400 volts. The electrode 2 soon begins to glow and gives off a con- 80 siderable quantity of light. Its appearance is much like that of a piece of heated iron which is cooling off from the white to the yellow stage. With higher current density, a bright sparkling effect begins to appear 85 over the entire surface of the luminous electrode, small brilliant spots of light appearing and then vanishing almost immediately. The light, however, is not dependent upon this sparkling condition, as the plate is 90 strongly luminous before sparkling is noticeable. In the case of aluminum alloyed with both manganese and copper, the light emitted has a peculiar bluish tinge, probably caused by some reaction in 95 which the copper is involved.

In Fig. 2, is shown a form of my invention in which electrodes 8 and 9, connected to the terminals of a source 10 of alternating-current, are suspended in an aqueous 100 bath 11 in a transparent container 12. In this form of the invention, a film is formed upon each of the electrodes 8 and 9 by independently subjecting them to the treatment described in connection with the formation of film 7 upon electrode 2. Electrodes 8 and 9 are then assembled and connected as shown. The operation is, in all essentials, the same as that described in connection with Fig. 1, except that the elec- 110

trodes, which are alike and which successively act as anodes, both become luminous.

The lamp shown in Figs. 3 and 4 comprises concentric cylindrical electrodes 13 and 14 sealed in a container 15 and having their conducting leads sealed into the container at its ends. Container 15 is formed of glass or other transparent material.

A modification of the structure of Fig. 3 that is illustrated in Fig. 5, comprises a carbon electrode 16, a metallic electrode 17 and a transparent container 18.

In each of the forms of my invention, any desired or well-known means for supporting the electrodes may be employed.

While I am not prepared to state the exact theory of the phenomena involved, it would appear that the electrical energy gives rise to chemical reactions at the surface of the positive electrode which set up vibrations within the range of light waves at the surface of the electrode.

It appears that the quantity of light is a function of the current density at the surface of the electrodes. The quantity of light depends also upon the composition of the luminous electrode and, in the case of aluminum alloyed with manganese, the quantity of light increases with increase in the proportion of manganese in the alloy.

It will be seen that this invention has a wide range of applications in the industries, since the conversion from electro-chemical or chemical energy, as the case may be, to light energy, is accomplished without production of heat. It is, therefore, possible to operate a lamp of this character in locations

where heat production is undesirable or even dangerous. The emitted light appears to be of particularly good quality. Since heat loss, which occurs in the ordinary method of producing light by means of incandescent substances, is largely avoided, it should be possible, by using suitably designed lamps according to my invention, to secure very much higher efficiency in the conversion of electrical energy to light energy than has heretofore been obtained.

While I have illustrated several conventional forms which my invention may take, it is to be understood that the structure and materials which I have specifically described may be variously modified by those skilled in this or related arts without exceeding the limits of my invention, which is, therefore, to be restricted only by the scope of the appended claims.

I claim as my invention:

1. A light-producing device including a plurality of film-forming electrodes formed of an alloy comprising aluminum, manganese and copper, a suitable electrolyte surrounding the electrodes and a transparent container therefor.

2. A light-producing device including a plurality of film-forming electrodes formed of an alloy comprising aluminum and manganese, a suitable electrolyte surrounding the electrodes and a transparent container therefor.

In testimony whereof, I have hereunto subscribed my name this 22nd day of Oct., 1917.

JOHN COULSON.
